John Ernest KENNEDY, Inventor

By Attorney *J. Marion*

UNITED STATES PATENT OFFICE.

JOHN ERNEST KENNEDY, OF MONTREAL, CANADA.

SHOE-SOLE.

SPECIFICATION forming part of Letters Patent No. 588,768, dated August 24, 1897.

Application filed October 30, 1896. Serial No. 610,538. (No model.)

To all whom it may concern:

Be it known that I, JOHN ERNEST KENNEDY, a citizen of the Dominion of Canada, residing at the city and district of Montreal, in the 5 Province of Quebec, Canada, have invented certain new and useful Improvements in Shoe-Soles; and I do hereby declare the following to be a full, clear, and exact description of the invention, such as will enable others skilled 10 in the art to which it appertains to make and use the same.

This invention relates to shoe-soles; and it consists in the novel construction and combination of the parts hereinafter fully described 15 and claimed.

In the drawings, Figure 1 is a longitudinal section through a shoe provided with a sole according to this invention. Fig. 2 is a detail plan view of the corrugated middle sole.

20 A is the shoe-upper, which is secured to a strip of leather, insole, or welt *a'* in any approved manner.

B is a layer of thin flexible material, such as canvas, coated or impregnated with india-25 rubber, and E is the middle sole, secured on the upper side of the layer of canvas B, which forms a projecting flange *b* around its outer edge. This flange *b* is secured to the strip 30 of leather, welt, or insole in any approved manner.

C is the outer sole, which may be of leather, india-rubber, felt, or other approved material. The outer sole C is secured under the canvas 35 layer B in any approved manner. The heel *C'* is also formed and secured in position in any approved manner.

D is a perforated insole secured above the middle sole inside the shoe. This insole may be made of leather, felt, cotton, or other ap-40 proved material.

The middle sole E is formed of india-rubber and is corrugated alternately on each side in such a manner as to render it collapsible. The corrugations *e* of the middle sole are arranged 45 crosswise, and *e'* are small holes connecting the upper and lower corrugations.

E' is a central longitudinal channel connecting the corrugations on each side of the sole with a space *f* in front of the heel portion, 50 and *E''* is another channel around the heel

portion and connecting the corrugations of such heel portion of the sole with said space *f*. The space *f* does not require to have corrugations, as there is little pressure at this point.

F is an air-tube connected to the space *f* or 55 lower interior of shoe and extending up the side of the shoe to the outer air.

When the foot descends in the act of walking, the middle sole collapses under the pressure of the foot and the air is forced out of 60 the corrugations *e* up the tube. When the foot is raised, the elasticity of the middle sole restores the corrugations to their original positions and draws air from the exterior of the shoe into the corrugations. In this manner 65 a constant circulation of air is established through the middle sole. This circulation of air keeps the shoe thoroughly ventilated and adds greatly to the health and comfort of the wearer.

If desired, the air-tube may be dispensed with and the corrugations of the middle sole 70 may be connected with the outer air in any other approved manner.

The collapsible sole also acts as a cushion, 75 preventing jar to the frame in walking and giving more room to the foot when stepping upon, as the foot then sinks into the space previously occupied by the insole. This relieves the strain on the leather across ball of 80 foot and permits the foot to expand naturally without increasing the exterior width of the shoe.

What I claim is—

1. A collapsible middle sole provided with 85 corrugations *e* arranged alternately on opposite sides of it, holes *e'* connecting the upper and lower corrugations, and a longitudinal channel *E*, substantially as set forth.

2. A collapsible middle sole provided with 90 corrugations *e* across its sole and heel, a space *f* on its under side between its sole and heel, and a longitudinal channel *E* connecting the corrugations of the sole with the said space, said corrugations being arranged alternately 95 on opposite sides of it and connected by small holes *e'*, substantially as set forth.

3. A collapsible middle sole provided with corrugations *e* arranged across its sole and heel, a space *f* on its under side between its 100

2
sole and heel, a longitudinal channel E connecting the corrugations of the sole with the space f, and a curved channel connecting the corrugations of the heel with the space f, the 5 said corrugations being arranged alternately on opposite sides of it and connected by small holes e', substantially as set forth.

In testimony whereof I affix my signature in presence of two witnesses.

JOHN ERNEST KENNEDY.
